UNITED STATES PATENT OFFICE.

CHARLES WELLMAN, OF NEW YORK, N. Y.

IMPROVEMENT IN SIDE-SADDLE TREES.

Specification forming part of Letters Patent No. 40,524, dated November 3, 1863.

To all whom it may concern:

Be it known that I, CHARLES WELLMAN, of the city and State of New York, have invented, made, and applied to use a certain new and useful Improvement in Trees or Bodies for Side-Saddles; and I do hereby declare the following to be a full, clear, and exact description of my said invention, reference being had to the annexed drawings, making part of this specification, wherein—

Figure 1 is a perspective view of such saddle-tree, and Fig. 2 is an inverted plan of the same.

Similar marks of reference denote the same parts.

The saddle-tree usually employed for side-saddles is very liable to break, because the wood cannot be very heavy at the parts joined together by tenons in mortises. Beside this, the length of the saddle from front to back is such that when the animal's back curves downward by the continuous weight thereon, the saddle rests most heavily at the front and back parts in a manner uneasy for the horse.

The nature of my said invention consists in a yielding tree or body for side-saddles, made of sole-leather and stiffened with strips of metal, which also cause it to resume its shape after being bent or twisted, these strips of metal running in a peculiar manner to afford the requisite stiffness.

In the drawings, *a* is the body or saddle-tree, formed of thick sole-leather, pressed into shape between dies, or otherwise formed, and the same may be made of one piece of leather, or of more than one piece, the parts being united by glue or otherwise.

c is the pommel or horn, and *b b* the pendants or legs taking the girth.

d is a metal strap extending along inside the legs *b* and across the saddle, and *e* is another metal strap passing on the outside of the saddle up the part *b* and pommel, and *h* is a metal strap across the front of the saddle, extending up inside the pommel, so that the same will be rendered strong and rigid. These straps *d*, *e*, and *h* are to be riveted together through the leather body *a*.

f f are metal straps extending from the strap *d* along the side portions of the body *a* beneath the same, and riveted to such body *a*; and *g* is a metal plate on the upper side across the back part of the saddle.

It will now be evident that a side-saddle body can be made very light by this construction, and at the same time is very strong. Only a thin padding or cushion is required under this saddle, and the yielding nature of said body allows it to conform to the shape of the animal's back, thus avoiding the fitting heretofore necessary to make the saddle set properly to the horse's back; and this saddle cannot slip on the horse, and is not liable to become broken in use.

What I claim, and desire to secure by Letters Patent, is—

The saddle tree or body for side-saddle, formed of sole-leather, with the metallic straps applied thereto, as specified.

In witness whereof I have hereunto set my signature this 17th day of September, 1863.
